J. E. CLARKE,
FLY CATCHER.
APPLICATION FILED SEPT. 13, 1915.

1,195,559.

Patented Aug. 22, 1916.

UNITED STATES PATENT OFFICE.

JAMES E. CLARKE, OF WORCESTER, MASSACHUSETTS.

FLY-CATCHER.

1,195,559.

Specification of Letters Patent. Patented Aug. 22, 1916.

Application filed September 13, 1915. Serial No. 50,309.

To all whom it may concern:

Be it known that I, JAMES E. CLARKE, a citizen of the United States, residing at Worcester, in the county of Worcester and 5 State of Massachusetts, have invented a new and useful Fly-Catcher, of which the following is a specification.

This invention relates to a fly catcher of that type in which a fly paper is supported 10 on a light frame which is moved over a surface on which the flies are gathered and is provided with a fly paper for tangling the flies which rise from said surface.

The principal objects of the invention are 15 to provide a light and cheap frame for this purpose and especially to provide it with means whereby a fly paper can be removed from it and applied to it readily without waste of time; to provide improved means 20 for holding the fly paper in position; and to provide a simple and inexpensive means for keeping the sticky side of the fly paper out of contact with any surface on which the device may be placed.

25 Further objects and advantages of the invention will appear hereinafter.

Reference is to be had to the accompanying drawings, in which—

Figure 1 is a perspective view of a preferred embodiment of the invention; Fig. 2 is an end view of the same, and Figs. 3 and 4 are perspective views of other forms in which the invention can be carried out.

Referring first to Figs. 1 and 2 it will 35 be seen that the invention is shown in a form in which it comprises a main frame formed of wire. This frame comprises a handle 10 formed by twisting the wire together. The wires at the ends of the handle 40 are extended out on both sides of the handle in opposite directions and at the ends are provided with offsets 11 and then are bent at right angles to form legs 12. From these legs extend two supporting wires 13 parallel 45 with each other and they at their ends are bent in the same plane and provided with two yielding members 14 which constitute paper retaining means. These are ordinarily looped under the projections 11 to hold

50 the former in position. It will be noted that the parts 12, 13 and 14 are in the same plane and the planes of the two members involving these parts are parallel and constitute the two sides of the device. This supporting frame is intended to hold a fly paper 55 20 which is doubled on itself so as to form

passages through it for receiving the members 14, and in this form it has two passages at the edges. It will be understood that the fly paper proper or sticky surface is on the 60 inside of the structure as thus produced.

In the use of the device the ends of the wires 14 are disengaged from the offsets 11 and the fly paper put in position on the wires 14, then their ends are reengaged to 65 hold them in position. The article is used by moving it along a surface on which the flies are gathered, either in contact with it or a slight distance from it. It does not have to be moved with great speed and is 70 preferably held so that the paper is nearly at right angles with the surface as it is being moved. It can also be hung up on a hook by the handle and will serve as a fly catcher of the ordinary standard kind in that case. 75 It can be rested on a flat surface on the supports 13, and in all cases they serve to keep the sticky paper out of contact with the surface.

In the form shown in Fig. 3 the conditions are substantially the same except that the two members 14^a which correspond with the two members 14 are connected by a wire 15 and in this case the fly paper 20^a is also doubled on itself but it is in a tubular form. 85 As the whole structure is constructed the two wires 14^a and 15 have to pass through the space between the two portions of the paper in the same way as in the construction shown in Fig. 1. The wire 15 is held in position by a single offset 11^a.

In the form shown in Fig. 4 the construction is very similar except that the handle is replaced by a loop 10^b by which the device can be hung up. The other parts are 95 shown as similar to those shown in Fig. 1 except that the supporting wire 13^b is flat to permit the device to rest stably on a flat surface. In this case it is used simply as a support for the fly paper and is not intended 100 to be moved when in use. In this case I have shown a protecting paper 21 on the fly paper proper which is intended to be peeled off to expose the sticky surface of the fly paper.

105 Although I have shown and described only three forms of the invention, I am aware of the fact that many other modifications can be made therein by any person skilled in the art without departing from 110 the scope of the invention as expressed in the claims. Therefore, I do not wish to be

limited to the details of construction herein shown and described, but

What I do claim is:—

1. As an article of manufacture, a fly catcher comprising a horizontal supporting frame having a relatively movable horizontal projecting portion in a plane parallel with, and spaced a short distance from, said frame, and adapted to pass through a fly paper per doubled over on itself for holding the same in position.
2. As an article of manufacture, a fly catcher comprising a frame having a movable projecting portion adapted to pass through fly paper doubled over on itself, said frame being provided with means for engaging the end thereof and holding the same against motion away from the main part of the frame.
3. As an article of manufacture, a fly catcher comprising a frame formed of wire having a free projecting portion adapted to retain a fly paper, said frame having integral projecting means for engaging the free end thereof and holding it in fixed position against motion away from the rest of the frame.
4. As an article of manufacture, a fly catcher comprising a wire frame having two

ends each consisting of a supporting wire 30 and a paper retaining wire in a plane with each other, said paper retaining wire being adapted to pass through the space between the parts of a doubled fly paper, the first named wire having projecting means integral therewith for holding the end of said paper retaining wire.

5. As an article of manufacture, a fly catcher comprising a wire frame having two ends each consisting of a supporting wire 40 and a paper retaining wire in a plane with each other, and integrally connected, the first named wire having inwardly projecting means integral therewith for holding the end of said paper retaining wire, said ends 45 being connected together at the center of the frame.

6. As an article of manufacture, a fly paper of a flattened generally tubular form provided with a free passage therethrough 50 from end to end closed at both sides and open at both ends having a substantially uniform width between said closed sides and having a sticky surface on one exposed side.

In testimony whereof I have hereunto set 55 my hand.

JAMES E. CLARKE.
